WiiMotion Plus Fine Tunes Wii Controller, Jul. 15 2008, <http://www.digitaltrends.com/e3/wiimotion-plus-fine-tunes-wii-controller/>.*
Pending U.S. Appl. No. 29/293,947, filed Dec. 19, 2007.

Primary Examiner — Angela Lee

(74) *Attorney, Agent, or Firm* — Nixon & Vanderhye, P.C.

(57) **CLAIM**

The ornamental design for a controller cover, as shown and described.

DESCRIPTION

FIG. 1 is a front, top and left perspective view of a controller cover showing our new design;

FIG. 2 is a rear, bottom and right perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof; and,

FIG. 9 is a front view of the controller cover showing the controller cover in use where the controller is shown in broken lines.

The subject matter shown in broken lines in FIGS. 1-3 and 9 forms no part of the claim design.

1 Claim, 4 Drawing Sheets
